Patented Oct. 24, 1922.

UNITED STATES PATENT OFFICE.

LAURA J. WOLFE, OF WHITMAN, MASSACHUSETTS.

MOP HOLDER.

Application filed August 19, 1921. Serial No. 493,563.

To all whom it may concern:

Be it known that LAURA J. WOLFE, a citizen of the United States, residing at Whitman, in the county of Plymouth and State of Massachusetts, has invented certain new and useful Improvements in Mop Holders, of which the following is a specification.

My invention relates to holders for mops or the like.

10 An important object of the invention is to provide a device of the above mentioned character which is simple in construction and can be accordingly manufactured at a low cost.

15 A further object of the invention is to provide a novel form of holding means for retaining the jaws of the holder closed, such holder means being itself securely held against accidental displacement.

20 Further objects and advantages of the invention will be apparent during the course of the following description.

In the accompanying drawings forming a part of this specification and in which like numerals are employed to designate like parts throughout the same,

Fig. 1 is a perspective view of a mop embodying my invention,

Fig. 2 is a similar view of the mop holder, the mop being omitted and the parts closed,

Fig. 3 is a similar view of the mop holder, the parts being opened, and,

Fig. 4 is a side elevation of the device, with the parts closed and the mop within the holder.

In the drawings, wherein for the purpose of illustration is shown a preferred embodiment of my invention, the numeral 5 designates a handle provided at its rear end with an eye 6 in order that the same may be hung upon a hook or the like. The forward end of the handle carries a ferrule 7.

The holding jaws of the device are formed from a singular section of wire, bent transversely upon itself at 8 and continued beyond this bent portion 8 in straight jaw sections 9. The wire is again bent transversely at 10, and continued rearwardly in the form of straight jaw sections 11. Sections 11 are spaced from and arranged opposite sections 9, and these sections are included in the pair of oppositely arranged jaws. The sections converge at 12, at their rear ends, and these converging portions are twisted at 13, and are embedded within the

forward end of the handle 5, inwardly of the ferrule 7.

The holding element embodies a transverse loop 14, adapted to receive the two jaws embodying sections 9 and 11, Figures 1 and 2. The loop 14 is formed of wire and one end of the loop is continued in the form of a straight shank 15, having a laterally bent hook 16 at its rear end. The shank 15 is adapted to operate within the diverging portions 12 and the hook 16 engages over these portions at the point of twisting, as shown. The loop 14 when moved forwardly upon the jaws also engages a scrubbing element 17, which may be a rubber sponge or the like. This scrubbing element is held between the jaw sections 11 and 9 of the opposed jaws. The sponge 17 being resilient it tends to move the loop 14 rearwardly, and locks the hooked end 16 and the shank 15 is securely locked in engagement with the twisted portion 13.

In the use of the device the rounded end 16' of the hook 16 may be engaged with the forward end of the thumb whereby the holding element is shifted forwardly longitudinally. This will enable the hook 16 to be disengaged from the twisted portion 13 and the loop 14 may then slide off of the jaw section 9, this jaw then moving away from the opposite jaw. The desired scrubbing element such as a rubber sponge may now be inserted between the jaws and the jaws moved together. The loop 14 is now passed over the upper jaw and the loop moved forwardly so that the hook 16 may be engaged over the twisted portion 13.

It is to be understood that the form of my invention herewith shown and described, is to be taken as a preferred example of the same, and that various changes in the shape, size and arrangement of parts may be resorted to without departing from the spirit of my invention or the scope of the subjoined claims.

Having thus described my invention, I claim:

1. A mop holder of the character described comprising a jaw formed of a spaced pair of sections of wire which have their rear ends twisted, a co-acting jaw connected to the first named jaw and extending longitudinally thereof, a loop permanently mounted upon the first named jaw and adapted to be placed upon and removed from the sec-

ond named jaw, such loop carrying a longitudinal shank having a hook to engage over the twisted portion of the first named jaw, and a handle having the twisted portion of 5 the first named jaw secured thereto.

2. A mop holder of the character described comprising a jaw formed of a pair of spaced sections of wire having their rear ends twisted, said sections of wire being bent 10 transversely at the forward ends of the first named jaw to form a second jaw disposed opposite the first named jaw, a loop slidably mounted upon the first named jaw and adapted to receive the second named jaw, 15 said loop having a shank provided with a hook to engage the twisted portions of the first named jaw, and a handle carrying said twisted portions.

3. A mop holder of the character described comprising, a pair of oppositely dis-

posed yieldable jaws, one of said jaws including a pair of elements spaced apart through the major portions of their length and connected to form a V-shaped crotch at their rear end, a loop slidably mounted upon the jaws, and a rearwardly extending shank secured to the loop and having a hook to engage with said V-shaped crotch. 25

4. A mop holder of the character described comprising a jaw embodying a pair 30 of spaced elements connected to form a V-shaped crotch adjacent their connected ends, an opposed co-acting jaw yieldably connected with the first named jaw, a loop slidably mounted upon the jaws, a shank secured to 35 the loop and having a hook to engage with said V-shaped crotch, and a handle secured to the rear end of the first mentioned jaw.

In testimony whereof I affix my signature.
LAURA J. WOLFE.
